UNITED STATES PATENT OFFICE.

WALLACE M. GIFFEN, OF ALAMEDA, CALIFORNIA, ASSIGNOR OF ONE-THIRD TO NELSON W. THOMPSON, OF OAKLAND, CALIFORNIA, AND ONE-THIRD TO GEORGE C. NOBLE, OF BERKELEY, CALIFORNIA.

OUTLET-VALVE SYSTEM.

Application filed June 19, 1922. Serial No. 569,481.

To all whom it may concern:

Be it known that I, WALLACE M. GIFFEN, a citizen of the United States, residing at Alameda, county of Alameda, and State 5 of California, have invented a new and useful Outlet-Valve System, of which the following is a specification.

This invention relates to valve systems having in view, safety first, and is primarily adapted for use in connection with liquid fuel containers. As an example of its adaptation, and for simplicity and convenience, I shall illustrate and describe my invention as applied to the common tank 10 truck, which delivers liquid fuel products to service stations, garages and other users of the same.

In such trucks, any injury to the dispensing valve, as being broken off in a 20 rear-end collision, may involve a considerable loss, and most frequently a total loss of the contents of its tank. In cases where an auxiliary or cut-off valve, is in the discharge line and close to the tank, and 25 adapted to be manually operated to close the same, a serious loss may also result, especially, if such valve is reached from underneath the tank, or from the top of it, because of the time that may elapse between 30 the accident and the driver's recognition of it, and the time required for him to reach the cut-off valve and close it.

As the contents of the tank truck are of an inflammable nature, any damage done 35 to the dispensing valve and its piping, may not only lose the contents of the tank, but the gases arising from the flowing gasoline or other highly volatile petroleum product, may render the approach to the cut-off 40 valve impossible or inadvisable. At such times a more serious consequence, is the ever present danger element of fire with its inherent disastrous results to life, limb and property.

45 The principal object of my invention is to automatically prevent the loss of the tank contents when an accident occurs to its outlet system, and thereby overcome and eliminate the above losses and dangerous situations that exist at such times.

I accomplish the above, by arranging two valves to normally open and close in series, and so connect them that the operation of the main valve determines the operation of

the auxiliary valve. I further provide 55 means, preferably a spring, to automatically close the auxiliary valve, should the main valve be broken off, the connection between the two valves being a tension device, the tension wire thereof is adapted to 60 restrain the spring or other closing means as long as it is in tension, and when not in tension, the auxiliary valve, induced by the said spring closes automatically.

Another dangerous situation other than 65 damage to the outlet system may occur, namely: The dispensing valve may be functioning, and the out-flowing gasoline or other product through the valve-spout take fire, and the operator be unable to 70 close the valve. Therefore, another object of prime importance is, that when such an accident occurs, the operator may manually close the auxiliary valve from a remote distance from the dispensing valve, as from 75 the front of the truck.

With the above and other objects in view, my invention consists in certain novel features of construction, form and arrangement of parts. The accompanying sheet 80 of drawings, forming a part of this specification illustrates but one embodiment of my invention, and what I claim as new, is particularly pointed out in the appended claims following the specification. 85

Figure 1 of the drawings, shows in side elevation, a conventional representation of the rear part of a tank-truck, and, applied thereto and partially shown in section, are two valves and their connections, all of 90 which are in accordance with my invention.

Figure 2 is a diagrammatic plan, showing a plurality of dispensing valves fed from the one tank outlet.

The light dot and dash lines represent the 95 tank and tank out-let flange respectively, above the valve system.

In the figures;—1 represents the tank, and 2 the rear wheels of a tank truck. 3 is the main valve which dispenses the fluid 100 contents of the tank, and which may be the ordinary valve used for this purpose, and 4 is its housing. 5 is a pipe extending from valve 3 to a fitting 6, which latter connects with tank outlet flange 7. Within the flange 105 and seated thereon is a reciprocating safety valve 8, adapted to open inwardly in the tank, against the pressure of a spring 9.

One end of the spring is seated within a cup on the valve 8, and the other end seated similarly on a bracket 9' which is fixedly secured to the tank.

5 Thus, liquid from the tank must pass through the internal valve 8, which I term the "auxiliary" valve, into pipe 5, thence through valve 3 to the outlet 10. Upon turning the handle 11, through a limited angle, valve 3 is withdrawn from its seat, and by this movement, oscillates a bell-crank 12 upon a shaft 13 within the housing 4. Bell-crank 12 pulls on a tension wire 14, which, in turn oscillates a lever 15 supported on rock-shaft 16 within the fitting 6. The lever 17 through a push rod 18, pushes up valve 8 and opens it, so that liquid from the tank flows through the two valves and the pipe 5, and out at 10. Upon closing valve 3, tension on wire 14 is released and valve 8 is automatically closed by spring 9.

In the valve system of Figure 2, the rock-shaft 16 extends from fitting to fitting, an end thereof being supported in each of the said fittings as at 19. Intermediate the fittings is a pipe 20, having at about its midway point a fitting 21 adapted to connect to tank flange 7. Push rod 18 and lever 17 carried by the rock-shaft are housed within the latter fitting.

In this arrangement of a plurality of dispensing valves 3, either one of the latter may open the internal valve 8, the compression imparted to the tension wire 14 in the unoperated valve, simply buckles the wire in the ample space of its pipe 5, and without injury to any parts.

40 To manually close the auxiliary valve 8, I provide the fitting 6 with a stuffing box 22 of any approved design, and preferably round the same at both extremities to facilitate the operation of a wire 23 therethrough. One end of the wire may be connected to the lower end of push rod 18, and the other end terminate at the driver's seat or other handy place remote from the dispensing valve 3.

Should the valve system be in dispensing 50 operation, and an emergency arise requiring that the auxiliary valve 8 be closed and from a remote distance from the outlet 10, a pull on the wire 23, will cause the push rod 18 and adjacent parts to assume an angular 55 position on the other side of the vertical center line as shown by the light dot and dash lines, thus closing the valve 8 and rendering the situation innocuous. After 60 subsidence of the emergency, the plug to fitting 6 may be removed and the push rod be poked back with any chosen tool to its normal operative position.

I claim:

65 1. A liquid container, having an outlet valve system, including two valves remotely 130

spaced and joined by a section of pipe but acting in series and substantially at right angles to each other, the main valve of which being manually operated, and the auxiliary valve being automatically operated in the closing thereof. 70

2. A liquid container, comprising, in combination, a main valve, a bell-crank oscillated thereby, an auxiliary valve, a lever connection adapted to open the same, a spring adapted to close said auxiliary valve, and a tension wire forming the connection between said bell-crank and lever connection. 75

3. A liquid container, having an outlet valve system, including, a main valve, means for manually operating said valve, an auxiliary valve acting in series with said main valve, means for automatically closing said auxiliary valve, a tension wire and connections between said valves, adapting said auxiliary valve to be opened by said main valve. 80

4. A liquid container, having an outlet valve system, including, an external valve and an internal valve remote therefrom and continuous operative connections therebetween, both valves adapted to act in series, the internal valve further adapted to close automatically and independently of said external valve should the operative connections be broken away, the said internal valve having a flange and T-fitting therefor adapted to house and support the mechanism of said valve. 90

5. In a liquid fuel tank, an outlet valve system including a safety valve secured to the tank and a dispensing valve spaced remote from the safety valve, said dispensing valve having tension means to open the safety valve simultaneously with its opening, and the safety valve further provided with means to automatically close in an emergency. 100

6. In a liquid fuel tank truck, a tank having an outlet valve system, including a safety valve and a dispensing valve and a tension member therebetween, the latter valve adapted to impart motion in tension to open the former valve, and the safety valve adapted to close itself automatically and simultaneously with the manual closing of the dispensing valve. 110

7. An outlet valve system for tank trucks, comprising, two valves, a pipe connection therebetween, and a wire member in said pipe attached to the valves; one of said valves adapted to be manually opened thereby imparting tension to the wire to open the other valve, but said last-named valve adapted to close automatically when tension on the said wire is released. 120

8. A valve system for tank trucks, comprising, a safety valve and a dispensing valve, a pipe connection therebetween for 130

remotely spacing the valves apart, and a wire member in said pipe connected to said valves, the safety valve forming part of the bottom of said tank, the dispensing valve adapted to open and close by a rotary motion and the safety valve adapted to open and close by a reciprocating motion, the opening of said safety valve being dependent upon the opening of the said dispensing valve through said wire member, but the closing of said safety valve being dependent upon spring means carried by said valve.

9. In a tank outlet system, an internal valve and a plurality of dispensing valves, connections therebetween, a tension device leading from each dispensing valve to a rock-shaft, said shaft provided with operative means for said internal valve, and any one of said dispensing valves adapted to open the internal valve independently of any other dispensing valve.

10. A liquid container, having an outlet valve system, including two valves acting in series, the main valve of which being manually operable, and the auxiliary valve

being normally automatically operable, but in an emergency the latter valve adapted to be closed manually.

11. In a liquid fuel tank, an outlet valve system, including a safety valve and a dispensing valve, the latter valve normally adapted to operate the former valve, the safety valve being provided with means to be manually closed independently of the closing of said dispensing valve.

12. A valve system for tank trucks, comprising, a safety valve and a dispensing valve, and connections therebetween, the safety valve forming part of the bottom of said tank, the dispensing valve adapted to open and close by a rotary motion and the safety valve adapted to open and close by a reciprocating motion, the opening of said safety valve being dependent upon the opening of the said dispensing valve, but the closing of said safety valve being dependent at times, upon spring means carried by said valve in conjunction with manually operable means connected therewith.

WALLACE M. GIFFEN.
